UNITED STATES PATENT OFFICE.

ADELARD B. SIMONEAU, OF WATERVILLE, MAINE.

HARNESS-ACTION FOR LOOMS.

1,378,732.

Specification of Letters Patent. Patented May 17, 1921.

Application filed January 18, 1920. Serial No. 352,438.

To all whom it may concern:

Be it known that I, ADELARD B. SIMONEAU, a citizen of the United States, residing at Waterville, in the county of Kennebec and 5 State of Maine, have invented certain new and useful Improvements in Harness-Actions for Looms, of which the following is a specification.

This invention relates to harness action 10 for looms, and has for an object to provide new and improved means for shifting the several harness units employed in weaving, and while the structure is expressly intended for hand looms for use in rag carpet 15 weaving, it is not limited to such utility and is applicable to other types of looms to weaving covering a considerable range of fabrics.

A further object of the invention is to 20 provide an improved means for raising the harness units against the tensions of retracting springs and releasing such units in timed relation with and actuated from the oscillation of the lay.

25 With these and other objects in view, the invention comprises certain novel constructions, units and combinations which will be hereinafter more fully described and claimed.

30 Referring to the accompanying drawings, which are made a part hereof, and on which similar reference characters indicate similar parts,

Figure 1 is a view of the loom in end 35 elevation, certain parts being broken away to show the harness suspension,

Fig. 2 is a longitudinal vertical sectional view,

Fig. 3 is a top plan view of the harness 40 actuating mechanism shown in normal or neutral position,

Fig. 4 is the top plan view of the harness actuating mechanism shown in position with the lay swung to shuttle actuating position 45 and certain of the harness actuating mechanisms moved away from neutral, and

Fig. 5 is a perspective view of the cam shaft for raising and lowering the harness-actuating bars.

50 The improved harness actuating mechanism which forms the subject matter of this application comprises upright levers 10 and 11, pivoted to the loom frame at 12, and actuated from the lay, which is here shown 55 conventionally at 13, by means of any approved connecting mechanism, as the links

14. It will be obvious, especially from Fig. 1, that as the lay 13 is oscillated, in the usual well known manner, the levers 10 and 11 will likewise be oscillated upon their fulcrums from the full to the dotted line position in Fig. 1.

The lever 10 carries upon its upper end a substantially triangular cam 15, the lever 11 carrying an equivalent cam 16. The 60 cams 15 and 16 are oppositely inclined as shown more particularly at Figs. 3 and 4. As the levers 10 and 11 oscillate upon their pivots 12 the cams 15 and 16 will reciprocate from the forward position shown at 65 Fig. 3 to the rearward position shown at Fig. 4 which is the limit of their movement. At Fig. 2 the position of the cams 15 and 16 is the same as at Fig. 4, to the extreme 70 limit of movement of the harness-moving mechanism.

Upon the frame of the loom, uprights 17 and 18 are employed supporting the fixed frame 19 having an auxiliary frame 20 slidable on the frame 19 and uprights 17 and 18, 80 as indicated at Figs. 3 and 4. At its opposite ends the auxiliary frame 20 is provided with cam blocks 21 and 22 in position to be engaged and moved by the cams 15 and 16 respectively through the path of movement indicated at Figs. 3 and 4, carrying therewith the auxiliary frame 20. It will be obvious that the swinging of the lay 13 and the actuation of the cams 15 and 16 therefrom will reciprocate the auxiliary 85 frame 20 alternately in opposite directions, making a complete cycle of reciprocation at each complete cycle of movement of the lay.

Bearing upon the uprights 17 and 18 and within the frame 19 are a plurality of bars, 90 here shown four in number, the number of bars depending upon the number of harness units employed. The bars shown, four in number as just stated for the purpose of illustration only, are numbered 23, 24, 25 95 and 26, it being understood that the invention is in no way limited to this number of bars.

Each of the bars 23 to 26 inclusive has suspended therefrom a harness unit. At 105 Fig. 2 the harness unit 27 is indicated as suspended from the bar 23 by the straps 28, passing over the rollers 29 secured to the bar in any approved manner as by the fastening member 30. The harness unit 31 110 is likewise suspended by the strap 32 passing over a roller co-axial with the rollers

29 and attached to the bar 24 at 33. Each of the bars 25 and 26 has a harness unit 34 and 35 suspended therefrom by the straps 36 and 37 in like manner.

5 The harness units are also provided with springs 38 exerting tension against the stress of the straps in lifting so that when the lift of the straps is released the harness units are returned to normal the stress exerted by their own weight augmented by 10 their respective attached springs.

Each of the bars 23 to 26 inclusive is provided with a shoulder 39 forming a hook, as indicated more particularly at Fig. 2, adapted, when free, to engage over the cam block 21, as shown at such Fig. 2, and to be moved by and with the cam block as indicated at Fig. 4. The movement of either of the bars 23 to 26 inclusive with the cam block 21 in the direction indicated at Figs. 2 and 4 obviously raises its attached harness unit as indicated at 27 by drawing the straps 28 over the rollers 29. It is also obvious that if all of the bars were free all 25 would simultaneously engage the block 21 and simultaneously raise all of the harness units. As this would not result in a weaving condition of the warp, means is provided for controlling the engagement of 30 certain of the bars with the block at certain intervals. This controlling means comprises a shaft 40 journaled in the frame 19 and provided with cam sections as indicated at 41 (see Fig. 5). With the cam sections 35 arranged as shown at Fig. 5 it is obvious that two of the bars, as for instance 23 and 25, will be in position to engage the block 21 while two of the bars, as 24 and 26, will be lifted by the shoulders 41, 42 out of the 40 path of movement of the block 21 as shown in Fig. 2. The rotation of the shaft 40 will vary the position of the shoulders which raise and lower the several bars 23 in an obvious manner. Rotation of the shaft is 45 provided for by employing a pawl 43, pivoted to the auxiliary frame 20 at 44, and engaging the teeth of the ratchet 45 upon the shaft 40 with each reciprocation of the frame 20. A detent 46 is also employed 50 bearing upon a multi-angular section 47 of the shaft 40 and with a spring 48 adapted to hold the detent in engagement with the section 47. The detent 46 is pivoted at 49 to the frame 19 and is employed to prevent 55 untimely turning of the shaft 40. A keeper 50 extends across and is secured to the frame 19 to prevent the bars 23 to 26 inclusive from being displaced. To limit the movement of the bars 23 to 26 inclusive under the 60 action of the springs 38 and weight of the harness units, stops 51 are formed upon the several bars, in position to engage the top of the upright 18 when in normal position as shown more particularly at Fig. 2.

65 In operation the swinging of the lay from

the full line position at Fig. 1 oscillates the levers 10 and 11 to reciprocate the auxiliary frame 20 and to carry therewith such of the bars 23 to 26 inclusive as are permitted to engage with the frame. The 70 movement of such bars lifts certain of the harness units connected therewith and places the warp in condition to permit the movement of the shuttle when the lay has reached the proper position therefor. The shuttle 75 motion is only conventionally indicated in Fig. 1 and forms no part of the present invention.

It is obvious that the shaft 40, which forms the controlling mechanism for the 80 bars and consequently for the raising of the harness units, may have its cams arranged in any order and any sequence that the exigencies of the weaving may make desirable. It is also obvious that the variation which may thus occur in the arrangement of the cams on the shaft 40 will control the type of weaving produced by the actuation of the loom.

Having thus fully described my said invention, what I claim as new and desire to secure by Letters Patent, is:

1. In a loom, a lay, a plurality of harnesses, means adapted to be selectively connected to the harnesses and movable transversely of the loom to operate such harnesses as are connected thereto and connections from the lay to the harness operating means to actuate the latter, substantially as set forth.

2. In a loom, a lay, shed forming devices, operating means for the shed forming devices movable transversely of the loom, means for connecting the shed forming devices selectively to said operating means, and means connecting the lay to said operating means to actuate the same, substantially as set forth.

3. In a loom shed forming devices, a frame extending across the loom and supported at both sides thereof, bars extending lengthwise of the frame and adapted for connection thereto, connections from the bars to the shed-forming devices and means to reciprocate the frame.

4. In a loom a plurality of harnesses, bars to operate individual harnesses, means slideable transversely of the loom to operate the bars, and means operating transversely of the first said means to move the same.

5. In a loom a harness unit, a frame extending across the loom and in sliding engagement with both sides of the loom frame, connections from the slideable frame to the harness unit and a member in sliding engagement with the frame for moving the frame.

6. In a loom, a lay, shed forming devices, a frame extending across the loom and supported at both sides thereof, means for con-

100

130

necting said shed-forming devices selectively to the frame, and means connecting the lay to the frame to operate the latter, substantially as set forth.

5 7. In a loom, a set of harnesses, a frame extending parallel to the harnesses, connections from the frame to the harnesses, and means for reciprocating the frame comprising a member movable longitudinally of the 10 loom and connected to the frame.

8. In a loom, a lay, a plurality of harnesses, a frame slidably mounted on the loom, means to connect the frame to the harnesses, and means to actuate the frame movable in synchronism with the lay and transversely of the motion of the slideable frame.

9. In a loom, a lay, a plurality of harnesses, a rocking lever adjacent to the lay, a link attached to the lay and also to the lever, 20 a frame mounted for movement transversely to that of the lay, means on the lever for imparting such movement to the frame, and connections from the frame to the harnesses.

10. In a loom, a lay, a plurality of harnesses, a frame having cams thereon and connected to the harnesses to operate them selectively, means attached to the lay to im- 25

part motion to the frame, said means including cams to act on the cams carried by the frame.

11. In a loom a plurality of harnesses, a frame and connections therefrom to the harnesses, means for imparting movement to the frame comprising rocking members carrying cams engaging the frame.

12. In a loom, a lay, a plurality of harnesses, bars connected to the harnesses and having hooks formed thereon, a movable frame adapted to engage the hooks, said frame having cam members at each end, 40 pivoted levers mounted parallel to the lay and beneath the frame, a link at each end of the lay connected to a lever, and a cam on each lever for engagement with the cams on the movable frame.

In witness whereof, I have hereunto set my hand and seal at Waterville, Kennebec county, Maine, this fifteenth day of January, 45 A. D. nineteen hundred and twenty.

ADELARD B. SIMONEAU. [L.S.]

Witnesses:

THOMAS N. WEEKS,
KATHERINE M. CHASE.
